UNITED STATES PATENT OFFICE.

CHARLES CARR, OF BOSTON, MASSACHUSETTS.

CASH-REGISTER.

SPECIFICATION forming part of Letters Patent No. 486,980, dated November 29, 1892.

Application filed June 8, 1892. Serial No. 436,018. (No model.)

To all whom it may concern:

Be it known that I, CHARLES CARR, a citizen of the United States, residing at Boston, county of Suffolk, and State of Massachusetts, have invented certain new and useful Improvements in Cash-Registers, of which the following, together with the accompanying drawings, having reference-letters, herein referred to, is a full and exact description.

10 Referring to the drawings, Figure 1 is a sectional end elevation of a machine embodying my improvements, the section being taken just within and parallel to the left-hand end frame F' in Fig. 3, the upper portion of the 15 machine being removed, as it bears no relation to my improvements. Fig. 2 is an enlarged end elevation of the adding device with the wheel g' removed. Fig. 3 is a sectional plan of the parts shown in Fig. 1. Fig. 20 4 is an enlarged front elevation of the adding device. Fig. 5 is a sectional detail view of wheels g and h, showing their connections. Fig. 6 is a perspective view of one of the 25 numeral-wheels and its attached parts. Fig. 7 is a perspective view of a numeral-wheel, its ratchet, and its operating-pawl. Fig. 8 is a 30 perspective view of a pawl D' and its stop or locking bar a'. Fig. 9 is a detail view of cam g', showing the notches therein to receive rollers h'.
35

The nature of my improvements relates to the total-adding mechanism and a positive stop and lock for the first moving gears, and these improvements are shown as applied to the machine illustrated and described in 40 United States Letters Patent issued to Charles Carr February 9, 1892, and numbered 468,329 and 468,330.

45 In this machine keys K and K', being levers of the first order, are arranged in groups of nine, each group representing a distinct decimal place. As here shown, there are two of these groups, one representing the units or "cent" place, the other the tens or "dime" place. These keys, which are pivoted at a, Fig. 1, have tappets k and k' upon the rear ends, and these tappets vary in length each from its neighbors in proportion to the digital 50 value of the keys. This variation will be readily understood by reference to Fig. 1. Each group of keys is spanned by a bail or rocking yoke B and B' for K and K', respect-

ively. These bails are also pivoted at a, and their rear ends normally rest against a stop-bar a', fixed in the frames F and F', which frames support the entire machine by means of the longitudinal shafts and rods aa'a'a', &c. The bails B and B' carry pivoted to them the pawls D and D', respectively, which pawls engage, respectively, with gears G and G', mounted loosely upon shaft a beside the bails. (See Fig. 3.) These gears are the first moving gears of the registering-train. A shaft a' in front of and below shaft a carries loosely mounted thereon the gears g, g', h, and h', of which g and g' mesh with and are driven by gears G and G', respectively. These gears g and g' each have an extended hub upon which is a flange g², to which is fixed a cam g³. (See Figs. 2 and 5.) Gears h and h' are loosely mounted upon said shaft a' and are constructed with the large hubs h⁴ recessed to receive the cams g³. In the peripheries of these cams are three notches, deep enough at one end to allow the loose rollers h² in said notches to just 70 touch the internal periphery of hubs h⁴, and the said notches taper gradually to nothing. It is evident that if the cam and its gear are turned in the direction of the arrow in Figs. 1 or 2 that the rollers will wedge into the 75 notches against the periphery of hub h⁴, causing sufficient friction to drive the gear h or h', as the case may be, while if either of said gears h or h' be turned by power applied directly to them, and in the same direction, 80 the rollers will tend toward the deep portion of the notch and thus free the cam from friction, allowing the gears h or h' to turn without turning or in any way disturbing the gears g and g'. This device permits the carrying process between numeral-wheels d and d' to be easily effected and makes the resetting of the numeral-wheels easier to accomplish.

85 The operation so far is readily understood—that is, when a key K is depressed the bail B corresponding to it being struck by the tappet k is raised or turned through an angle corresponding to the digital value of the key, and when the bail is released it is carried down by force of gravity or springs and the 90 pawl D pivoted thereon engages the teeth of gear G, and thus turns said gear through an angle corresponding to the value of the key. It will be seen that this also applies to keys

K', bail B', pawl D', and gear G', and also that though the motion of bails B and B' vary in length according to the value of the keys, they always stop in the same position, resting on stop-bar a'. It is obvious that the motion of gears G and G' will be transmitted to gears h and h', respectively, by means of gears g and g' and the one-way friction driving mechanism already described.

10 On the longitudinal shaft a⁴, located in front of and slightly above shaft a³, Fig. 1, are mounted the wheels d, d', d², d³, d⁴, and d⁵ of the adding device. These wheels bear upon their peripheries, as shown, two sets of digits, and will be called for convenience "numeral-wheels." Of these the right-hand one, Figs. 3 and 4, is lettered d and represents the cents place, the next wheel d' the dime place, and so on. The wheels d and d' have fixed upon the right-hand side the gears c and c', respectively, which mesh with and are driven by the gears h and h', respectively. Thus it will be readily seen that the keys K and K' drive their corresponding wheels in the adding device. As is readily understood the digits on the wheels appear consecutively at the sight-slot w, and as the number "9" leaves the position before the said sight-slot it is necessary to "carry" one to the next wheel. This process of carrying is effected by the following means and in the following manner: Each of the numeral-wheels (except the left-hand one d⁵) has fixed to the left side a disk or wheel e, which has 35 two teeth or cams f on its periphery, the remainder of the periphery being concentric with the axis of the wheels, and each of the numeral-wheels, except the first, has a ratchet r' attached to the right side. Supported in 40 the auxiliary frames F² and F³ is a shaft a⁵, parallel to shafts a³ and a⁴, upon which are pivoted the arms o, o', o², o³, and o⁴, upon each of which is a roller p, which rests upon the periphery of the disks e upon a lower wheel, 45 and upon the opposite side of which are the hooks s, said hooks acting with the teeth of the ratchets r of the next wheel above. Now the cams f are so arranged in relation to the digits on the wheels that when the digit "9" is 50 at the sight-slot the inclined side of said cam is just starting under the roller p, so that as the digit "9" passes the sight-slot the cam f raises the roller p and the lever to which it is attached, and the hook s, engaging the teeth of the ratchet r, turns the numeral-wheel one tooth or the space of one digit, this process of carrying being repeated throughout the series of wheels. The object of having two sets of digits and two cams upon the 55 numeral-wheels is to reduce the angular velocity of the said wheels.

It is desired at times to reset the adding device or rather to bring the numeral-wheels all to indicate "0," and the means by which this is accomplished is as follows: To the left of each of the numeral-wheels is a disk m, keyed to shaft a⁴ and having a tooth m', which acts

against a spring-pawl n, secured by a pin n' to the numeral-wheels. Thus, as is evident, if the shaft a⁴ is turned by the thumb-nut a⁹ in 70 the direction of the arrow in Fig. 2, the friction of the pawl n against tooth m will be sufficient to turn the wheel also. The turning of the wheel having been provided for it is necessary to have some device for stopping the 75 wheels at the desired position. In front of and below the numeral-wheels is located a longitudinal shaft a⁶, supported by the auxiliary frames F² and F³, upon which is pivoted a rocking frame u, having a handle u³ and 80 hooks u⁴, said hooks being in the same vertical plane as the pins n', but normally just out of the path of said pins. Now when it is desired to reset the numeral-wheels the handle u³ is raised, turning rocking frame u 85 on its pivots and bringing the hooks u⁴ into the paths of the pins n', when, if the wheels are caused to turn, as above, the pins n' strike the hooks u⁴, and the spring-pawls n slip over the teeth m', allowing the shaft to go on after 90 one wheel is stopped or until all the pins are brought against the hooks, and as the pins are located in proper relation to the "0" on the wheels the said figure "0" will be brought to the sight-slot. Now it is desirable to hold 95 the pawls s away from the ratchets during this process of resetting, and to accomplish this a bar t' is provided, which has fixed thereon spring-fingers s² in the plane of the hooks s but normally just removed from the 100 arms s' of said pawls s. This bar t' is slotted and serves as a guide for the levers o, o', &c., and is supported by rocking arms t, pivoted upon the frames F² and F³ and in the lower ends of which are pins t², which work 10 in cam-slots u² in the extended arms u' of rocking frame u. Now when the handle u³ is raised the arm u' is depressed, and the cam-slots u² being properly inclined push the pins t² backward, rocking the arms t, and bringing 11 the bar t' forward, so that the spring-fingers s² strike the arms s' of hook-pawls s, swinging them out of engagement with the teeth of ratchets r', as shown by dotted lines in Fig. 2.

Any retrograde movement in wheels d, d', d², d³, d⁴, and d⁵ is prevented by the counter-weighted pawls r, pivoted on shaft a⁶ and acting against the teeth of ratchet-wheels r'.

It is desirable in machines of this class that the first moving gear should be positively 12 stepped and locked in the position to which it is carried by the driving-pawl. In the drawings I have shown a lock-bar a⁷, having vertically-projecting locks or arms a⁸ for this purpose. The driving-pawls D and D' are 13 constructed with an inwardly-projecting arm D², against which a spring D³ or its equivalent acts to keep the pawls in engagement with the teeth of the gears, and the lock-bar a⁷ is so located that when the bails B and B', 14 with the pawls D and D', are in their normal or starting position—i. e., resting on the stop-bar a'—the locks a⁸ on bar a⁷ stand just under the arms D² on the pawls, preventing the

pawls from swinging out of engagement with the teeth of the gears until the bails are raised. As is obvious, this forms a positive stop and lock for the first moving gears G and G'.

5 A suitable case of wood or metal and of useful or ornamental design may surround and inclose the working parts.

Having described my improvements, what I claim is—

10 1. In a registering-machine having an adding mechanism in which the process of carrying is effected by means of cam-disks fixed to the numeral-wheels of lower value, each acting to lift a lever and hook-pawl, said hook-pawl engaging the teeth of a ratchet-wheel attached to the next higher numeral-wheel, thus turning said higher numeral-wheel through one units-space during the movement of the lower wheel through each tenth units-space, the combination of key-levers arranged in groups or banks, each group representing a different decimal place, a bail or yoke spanning each group and operated by the keys of said group, a driving-pawl pivoted on each of 25 said bails and each engaging the teeth of a separate main driving-gear, said driving-gears, the above-described adding mechanism, and suitable intermediate one-way driving mechanism connecting each of said main driving-gears to its corresponding numeral-wheel in the adding mechanism, all operating together, substantially as and for the purpose set forth.

2. The combination of keys K, bail B, pawl D, gears G and g, gears h and c, the one-way driving mechanism connecting gears g and h, numeral-wheel d, to which said gear c is attached, disk e, also attached to the numeral-wheel d and having upon its periphery the cam f, said cam, lever o, having roller p running on disk e, said roller, a hook-pawl s, pivotally attached to said lever, and ratchet r', attached to numeral-wheel d' and engaged by the said hook-pawl and said numeral-wheel d', all arranged and operating together, substantially as set forth.

3. The combination of the numeral-wheels, the shaft a⁴, upon which the numeral-wheels are loosely mounted, the disks m, keyed to the shaft and having each a tooth m', the 50 spring-pawls n, fixed upon the numeral-wheels by means of pins n', said pins, the rocking frame u, having hooks u⁴ formed thereon, and

said hooks, substantially as and for the purpose set forth.

4. The combination of the adding mechanism herein described, the resetting device therefor and the rocking arms t, cross-bar t', its attached spring-fingers s², the pins t² in the said rocking arms, the arms u', having cam-slots u², which from the connection with and by the action of the resetting mechanism act through and by means of pins t², arms t, bar t', and fingers s² to disengage the carrying-pawls of the adding mechanism, substantially as described. 55

5. The combination of the numeral-wheels, the ratchets r', shaft a⁴, disks m, having teeth m', spring-pawls n, pins n', rocking frame u, hooks u⁴, arms u', cam-slots u², pins t², arms t, cross-bar t', spring-fingers s², and pawls s, 70 having arms s', and said arms, all substantially as and for the purpose set forth.

6. In a registering-machine in which the first-moving gears are operated by the action of pawls carried by bails which have been raised and allowed to fall by the action of finger-keys, the movement of the said bails and pawls always stopping in the same position resting against a fixed stop-bar, the combination of keys, bails, pawls, gears, the stop-bar, and arms formed upon each of said pawls with fixed locks, which are so located that when the bails and pawls are in the resting position they act against the arms on the pawls and prevent the said pawls from swinging out 85 of engagement with the teeth of said gears, thereby forming a positive stop and lock for said gears, substantially as described. 80

7. The combination of the fixed pawl-lock a⁸, arm D², fixed to pawl D, bail B, carrying pawl D, said pawl D, lever K, spring D³ or equivalent pawl-mover, and the fixed stop-bar a', for the purpose of giving a specific and definite movement to the wheel G', substantially as described. 90

8. The fixed lock a⁸, in combination with pawl-arm D², and pawl D, for the purpose of locking the said pawl D in its engagement with gear G while at rest, substantially as described. 95
